UNITED STATES PATENT OFFICE.

HENRY H. WARNER, OF TACOMA, WASHINGTON.

SWITCH STAND AND LOCK.

SPECIFICATION forming part of Letters Patent No. 740,788, dated October 6, 1903.

Application filed December 15, 1902. Serial No. 135,346. (No model.)

To all whom it may concern:

Be it known that I, HENRY H. WARNER, a citizen of the United States, residing at Tacoma, in the county of Pierce and State of Washington, have invented a new and useful Switch Stand and Lock, of which the following is a specification.

My invention relates to improvements in railroad-switch stands in which the switch is operated by means of a handle rotated about a shaft or pivot; and the objects of my improvements are, first, to cheapen the cost of constructing switch-stands; second, to facilitate the rapid operation thereof, and, third, to protect the locking device so that it may not be readily tampered with. I attain these objects by the mechanism illustrated in the accompanying drawings, in which—

Figure 1 represents a general view of my switch-stand; Fig. 2, a vertical section of the upper portion thereof; Fig. 3, a front view of said upper portion; and Fig. 4 a plan of said upper portion, showing the part over the lock in section.

25 Similar letters of reference refer to similar parts throughout the several views.

A represents the upper plate or table of the switch-stand, through which the target-rod C passes. To this rod C is keyed in the usual manner the plate B, resting on the table A. The plate B is provided with a slot F on its outer edge and extending inward adapted to receive the handle D and to allow it to turn therein on the pivot E. Pivot E passes through 30 the plate B near its lower side in a direction at right angles to the line of slot F. The pivot E also passes through the handle D in the slot F, thus allowing it to turn on a horizontal axis in the usual manner. Plate B is provided with a recess (preferably cylindrical) placed at one side of the slot F and projecting inward from the outer edge on a radial line from the target-rod C. This recess is met by a smaller hole passing from slot F at 35 right angles to said recess. Into this recess is placed the cylindrical lock H, having its bolt I in the smaller hole and projecting into the slot F, said bolt I being pressed toward slot F by the spring L in the other end of said hole. Handle D is provided with a hole J, so placed as to receive the bolt I when said handle is hanging in a vertical position. Lock

H is protected from dust and water by the hanging cover K.

Plate A is provided with two or more slots 55 G in its outer edge adapted to receive the handle D in the several positions which said handle and plate B must be placed to properly operate the switch. Handle D only engages said slots G when hanging in a vertical 60 position. When the handle D is in said vertical position engaging one of said slots G, the bolt I, being then in hole J, prevents said handle from being turned on pivot E; but on withdrawing said bolt I it is evident handle 65 D may be disengaged from slot G and rotated on pivot E into a horizontal position, and rod C may then be turned by handle D and the switch thrown. At the present time switch-stands are made with the handle projecting 70 upward and provided with a lug having a hole therein, said lug passing through a slot in a projection cast on the top of plate B and with a detachable padlock adapted to engage the hole in said lug. This method 75 is very expensive, because of the constant loss of and damage to the padlock and also because of the time necessary to operate the same, often making it necessary for a long and heavy train to be brought to a dead 80 stop before the switch can be thrown, whereas with my improvement the operation is so much shortened that the switch can be thrown in about one-half the time usually taken at the present time, and my improvement 85 leaves nothing exposed which can be broken readily with a stone or other light tool likely to be found in the neighborhood. With my improvement the operator seizes the handle D in his left hand and, pushing to 90 one side the cover K with the key held in his right hand, inserts the key, and withdraws the bolt I, which releases handle D. He then turns the switch to the proper position and drops handle D in the corresponding slot G and at 95 the same time removes the key from the lock, and in removing the said key the bolt I enters hole J and the switch is locked.

It is evident that this improvement may be of many different forms than the one shown 100 and described above. For instance, the stand may be laid on its side and suitably changed to become what is known as a "ground-throw-switch." Also many forms of

locks may be used. Also bolt I may be made to engage the back of the handle D instead of the hole J.

What I claim as my invention, and desire 5 to secure by Letters Patent, is—

A switch-stand comprising a frame, a table secured to said frame, notches through said table in the outer edge thereof, a target-rod journaled in said frame, a flat solid plate resting on said table and secured to said target-rod, a vertical radial slot through said plate, a hand-lever pivoted in said slot near the lower outer edge of said plate and adapted to turn on said pivot from a horizontal un- 10 locked position to a vertical locked position and to engage said notches when in the locked 15

position, a spring-actuated bolt within a hole in said plate and pressing against the side of said hand-lever when said lever is in un-locked position and engaging a hole in the 20 side of said lever when said lever is in locked vertical position, and a cylindrical lock inserted in said plate and adapted to engage said bolt to withdraw it from said hole in said hand-lever to unlock said hand-lever. 25

In testimony whereof I have signed my name to this specification in the presence of two subscribing witnesses.

HENRY H. WARNER.
